REFRIGERATING MACHINE

Leonard W. Atchison, Schenectady, N. Y., assignor
to General Electric Company, a corporation of
New York

Application December 1, 1937, Serial No. 177,521
Renewed February 8, 1940

10 Claims. (Cl. 62—116)

My invention relates to refrigerating machines, and particularly to refrigerating machines having a plurality of evaporators maintained at different refrigerating pressures.

5 In order to provide household refrigerator cabinets or other spaces to be cooled with two or more temperature zones, a plurality of evaporators may be provided in the circuit of a refrigerating machine in such a manner that they 10 may be operated at different pressures and, therefore, at different temperatures. A plurality of evaporators may be connected in series in the refrigerant circuit of a refrigerating machine so that the second evaporator receives refrigerant 15 from the first evaporator and so on. The relative temperature of any two evaporators may then be regulated by controlling the rate of flow of refrigerant from the first of the evaporators to the second. Accordingly, it is an object of my invention to provide a refrigerating machine having 20 a plurality of evaporators and an improved arrangement for maintaining different temperatures in said evaporators and for controlling the distribution of refrigerant to the evaporators.

25 Further objects and advantages of my invention will become apparent as the following description proceeds, and the features of novelty which characterize my invention will be pointed out with particularity in the claims annexed to 30 and forming a part of this specification.

For a better understanding of my invention, reference may be had to the accompanying drawing in which Fig. 1 shows a household refrigerating machine provided with a cooling unit comprising a plurality of evaporators and embodying my invention; Fig. 2 shows an enlarged perspective view of the cooling unit shown in Fig. 1 with the doors thereof removed and with the control panel moved forward to a position in front of its 40 normal position in order more clearly to show the construction; Fig. 3 is a view of the inner evaporator shown in Fig. 2 in its form in the flat prior to bending; Fig. 4 is an enlarged sectional plan view of the control valve and distributing device of the cooling unit shown in Fig. 2; and Fig. 5 is an enlarged sectional elevation view of the distributing device shown in Fig. 2.

Referring now to the drawing, in Fig. 1 I have 50 shown a household refrigerating machine including a cabinet 10 having a door 11 for closing a food compartment 12. A cooling unit 13 supported from the removable top of the cabinet is arranged within the cooling compartment 12 55 to cool the compartment. The cooling unit 13

is connected in the refrigerant circuit of a refrigerating machine comprising a motor and a compressor arranged within a casing 14, a condenser 15 surrounding the casing 14, and a receiver or float valve chamber 16 mounted on the removable top of the cabinet. During the operation of the refrigerating machine, refrigerant is compressed by the compressor in the casing 14 and is discharged into the condenser 15 where it is cooled and liquefied by radiation and by the air circulating over the condenser by natural convection. The liquid refrigerant flows from the condenser through a connection 17 into the float chamber 16 and when a predetermined amount of liquid refrigerant has collected, a float 15 in the chamber rises and the liquid refrigerant flows through a liquid line 18 into the cooling unit 13. The liquid refrigerant in the cooling unit 13 is vaporized by the absorption of heat from the air within the cabinet and from articles placed within the cooling unit and the vaporized refrigerant is withdrawn from the cooling unit through a suction line 19 and returned to the casing 14 from which it is drawn by the compressor therein. The operation of the compressor 25 is regulated by a control device 20 having a thermostatic element 21 in heat exchange relation with the outer relatively high temperature wall of the cooling unit.

The construction of the cooling unit 13 is clearly shown in Fig. 2. This cooling unit is similar to that described and claimed in a copending application of Christian Steenstrup, Serial No. 177,495, filed December 1, 1937, and assigned to the same assignee as the present application. I do not herein claim anything described or claimed in the said Steenstrup application.

The cooling unit 13 includes an outer housing 22 comprising side and back walls formed from complementary inner and outer metal sheets 23 and 24 respectively, and the bottom wall comprising a single sheet 25 connected to the back and side walls. The compartment formed by the housing 22 is separated into an upper and a lower section by a double wall comprising metal sheets 26 and 27. Each of the side walls is provided with a header 28 formed in the upper portion thereof, which is maintained about half full of liquid refrigerant. The middle header formed in the back wall communicates with the headers in the side walls through passages 29 and 30 providing communication between the headers above and below the liquid level respectively. Each of the walls is provided with upright and transverse refrigerant passages 31 and 32 respectively, with-

in which liquid refrigerant is circulated, the upright passages 31 communicating with the headers 28 so that vaporized refrigerant may rise to the headers. The liquid line 18 discharges refrigerant into a manifold 33 which extends along the lower edge of the walls and which communicates with one of the upright passages in each of the walls through ducts 34 and thereby injects refrigerant into the upright passages to produce a circulation of refrigerant through the transverse passages. The range of temperature of the outer walls of the casing is regulated by the control device 20, so that the walls are maintained above the freezing point of water, or are allowed to periodically rise above freezing during at least a portion of the cycle and thereby cool the air within the food compartment 12 on a "defrosting cycle" without materially reducing the moisture content thereof, continuous frosting of the evaporator being prevented.

In order to provide a freezing chamber, a flooded evaporator 35 is provided in the upper portion of the housing. This evaporator as shown in Figs. 2 and 3 comprises a sheet metal structure having formed therein a header 36 and a plurality of U-shaped passages 37 communicating with the header below the normal level of the liquid refrigerant therein. The lower ends of the U-shaped passages 37 are connected by ducts 38 to a manifold 39 and the manifold 39 is connected to an inlet passage 40 by a sinuous conduit 41. The sheet metal structure, as shown in Fig. 3, is bent into the form shown in Fig. 2, so that the sinuous conduit 41 lies partially in a freezing shelf 42 and partially in a side wall 43 remote from the header 36. This construction provides a lower freezing compartment completely surrounded by refrigerant containing walls and an upper compartment formed by the side wall above the shelf 42 and a wall 44 providing an extension of the side wall 43. During the operation of the inner evaporator, the sinuous conduit 41 carries all the refrigerant admitted to flooded conduits of the evaporator and this conduit operates as a "non-flooded" passage, since it carries a large volume of gaseous refrigerant and a relatively small amount of liquid. The header 36 is normally maintained about half filled with liquid refrigerant, so that the U-shaped passages 37 are maintained flooded. In order to supply refrigerant to the inner evaporator 35, I provide a connection 45 communicating with the header 28 in the rear wall of the outer evaporator. The connection 45 opens into the header 36 near the normal level of liquid refrigerant therein. Therefore, when gaseous refrigerant is withdrawn from the header through the connection, any excess liquid refrigerant is withdrawn therewith. The liquid and gaseous refrigerant flow through the connection 45 to a manually adjustable valve or restricted passage 46 and from the valve to the evaporator 35 through a connection 47, an upright cylindrical vessel 48, and a connection 49. The connection 49 communicates directly with the passage 40 in the walls of the evaporator 35 below the level of liquid refrigerant therein and produces a circulation of liquid refrigerant by discharging a mixture of liquid and gaseous refrigerant into the circulating passages 37. Gaseous refrigerant collects in the header 36 and is removed therefrom through the suction line 19. The valve 46 restricts the passage of refrigerant from the outer evaporator to the inner evaporator and thereby maintains a pressure differential between the two evaporators, so

that the inner evaporator operates at a lower temperature than the outer evaporator. The differential of temperature may be varied by adjusting the valve 46. As shown in Fig. 4, the valve 46 comprises a valve stem or plunger 50 which may be moved axially in a valve block 51. The valve stem 50 is sealed by an expandable bellows 52 and the stem portion may be adjusted by turning a cam 53 which moves the valve stem in opposition to the force of a compression spring 54. A knob 55 is provided to turn the cam 53. A shoulder or stop 56 is provided to limit the closing movement of the valve stem 50, so that the valve can never be closed completely. The cam and valve are mounted in a bracket 57 secured to a panel 58, which is secured to the upper front portion of the cooling unit.

During some periods of the operation of the cooling unit, a large amount of gaseous refrigerant may be formed in the outer evaporator when there is little or no demand for cooling of the inner evaporator. Furthermore, even when there is demand for cooling of the inner evaporator, the amount of gaseous refrigerant formed in the outer evaporator may be greater than desirable for proper circulation of the refrigerant in the flooded portion of the inner evaporator. A large volume of gaseous refrigerant is particularly undesirable in evaporators provided with series or continuous conduits, such as the sinuous conduit 41, because the passage of a large volume of gas tends to move the liquid refrigerant quickly through the series conduit and the large volume of gas has little heat absorption capacity and, consequently, freezing loads placed on the series conduit in positions such as on the shelf 42 may not be sufficiently cooled. In some cases, it is even possible that ice on the shelf might be allowed to melt due to the loss of capacity and the relatively high temperature of the circulating gas. It is, therefore, desirable to reduce the proportion of gaseous refrigerant circulated through the inner or low temperature evaporator. As shown in Fig. 4, the liquid and gaseous refrigerant flowing from the valve 46 enter the upper vessel 48 through the connection 47 near the middle portion thereof and both liquid and gaseous refrigerant flow from the chamber or vessel 48 through the connection 49 to the inner evaporator. In order to remove a portion of the gaseous refrigerant, I provide a restricted duct 59 providing communication between the upper portion of the vessel 48 and the header 36, so that a limited amount of gaseous refrigerant is diverted from circulating through the passage 49 and the series conduit and flooded conduits of the inner evaporator.

The duct 59 is provided, so that the diverted gaseous refrigerant is led directly to the suction line 19 and withdrawn from the cooling unit without passing through the inner evaporator. By providing the passage 59 for diverting a portion of vaporized refrigerant, the mixture of liquid and gaseous refrigerant, which is conveyed to the inner evaporator, is made to have a greater proportion of liquid refrigerant than would otherwise be possible. Furthermore, since the duct 59 is restricted, there is a substantial pressure drop therein and the pressure drop from the inlet end of the conduit 40 to the outlet 19 of the inner evaporator is thereby maintained.

The cooling unit is secured to the top wall of the refrigerator cabinet by means of flanges 60 at the tops of the walls and the inner evaporator is secured to the top wall of the cabinet

on flanges 61. The upper and lower portions of the cooling unit compartment are closed by doors 62 and 63 respectively as shown in Fig. 1. These doors prevent the circulation of the cabinet air over the cold portions of the cooling unit and thereby reduce the dehydration of the air and food therein. The lower portion of the compartment is maintained at a temperature intermediate that of the food compartment and that of the freezing compartment. This intermediate temperature is suitable for the preservation of meats and similar foodstuffs.

During the operation of the refrigerating machine shown in the drawing, the control 20 operates to start the refrigerating machine and supply liquid refrigerant to the float chamber 16 whenever the temperature of the outer evaporator rises to a predetermined value. Liquid refrigerant is then admitted to the liquid line 18 and flows into the outer evaporator through the manifold 33. The headers 28 are maintained normally partially filled with liquid refrigerant and the passages 31 and 32 communicating therewith are kept flooded with liquid refrigerant. The air within the food compartment 12 is cooled by circulation produced by natural convection and a portion of the liquid refrigerant is vaporized thereby. A plurality of heat conducting fins 64 may be provided to increase the effective heat absorbing surface of the outer evaporator. The vaporized refrigerant and the excess liquid refrigerant flow from the header 28 in the rear wall through the connection 45 and thence through the restricted valve 46 to the chamber 48. The liquid refrigerant falls to the bottom of the chamber 48 and is discharged through the connection 49 with a substantial portion of the gaseous refrigerant. Some of the gaseous refrigerant flows from the chamber 48 through the restricted passage 59 and returns directly to the suction line 19 by way of the header 36. The relative volume of liquid refrigerant in the conduit 49 is, therefore, greater than that in the conduit 47 leading to the chamber 48. The inner evaporator is maintained flooded by the continual addition thereto of liquid refrigerant flowing through the sinuous passage 41 from the connection 49 and the liquid refrigerant flows through the series conduit at a rate providing substantial freezing capacity at all times. Refrigerant is vaporized within the inner evaporator and the vaporized refrigerant collects in the header 36 and is withdrawn therefrom through the suction line 19. When the temperature of the outer evaporator has been reduced sufficiently, the control 20 operates to stop the compressor and thereby stops the further supply of liquid refrigerant to the float valve chamber 16.

From the foregoing, it is readily apparent that I have provided an improved arrangement for controlling the flow of refrigerant in a refrigerating machine having a plurality of evaporators arranged in series and maintained at different temperatures.

While I have described my invention in connection with a cooling unit for household refrigerating machines, other applications will readily be apparent to those skilled in the art. I do not, therefore, desire my invention to be limited to the construction shown and described, and I intend in the accompanying claims to cover all modifications within the spirit and scope of my invention.

What I claim as new and desire to secure by Letters Patent of the United States, is:

1. A refrigerating machine including two evaporators, means for supplying refrigerant to one of said evaporators, means for conveying liquid and gaseous refrigerant from said one evaporator to the other of said evaporators, said other evaporator having a series conduit for carrying refrigerant through one portion thereof, means for withdrawing gaseous refrigerant from said other evaporator, means including a restricted passage arranged in said conveying means for maintaining a difference of pressure between said evaporators, and means communicating with said conveying means between said restricted passage and said series conduit for diverting from said series conduit a quantity of gaseous refrigerant.

2. A refrigerating machine including two evaporators, means for supplying refrigerant to one of said evaporators, means for conveying liquid and gaseous refrigerant from said one evaporator to the other of said evaporators, means for withdrawing gaseous refrigerant from said other evaporator, means including a restricted passage arranged in said conveying means for maintaining a difference of pressure between said evaporators, and means communicating with said conveying means between said passage and said other evaporator for diverting from said other evaporator a quantity of gaseous refrigerant.

3. A refrigerating machine including two evaporators, means for supplying refrigerant to one of said evaporators, means for conveying liquid and gaseous refrigerant from said one evaporator to the other of said evaporators, means for withdrawing gaseous refrigerant from said other evaporator, means including a restricted passage arranged in said conveying means for maintaining a difference of pressure between said evaporators, and means communicating with said conveying means and including a chamber arranged between said passage and said other evaporator and a tube connecting said chamber and said withdrawing means for diverting from said other evaporator a quantity of gaseous refrigerant.

4. A refrigerating machine including two evaporators, means for supplying refrigerant to one of said evaporators, means for conveying liquid and gaseous refrigerant from said one evaporator to the other of said evaporators, means for withdrawing gaseous refrigerant from said other evaporator, means including a restricted passage arranged in said conveying means for maintaining a difference of pressure between said evaporators, and means communicating with said conveying means between said passage and said other evaporator for diverting from said other evaporator a quantity of gaseous refrigerant, said diverting means being sufficiently restricted to maintain a substantial pressure drop across said other evaporator.

5. A refrigerating machine including two evaporators, means for supplying refrigerant to one of said evaporators, means for conveying liquid and gaseous refrigerant from said one evaporator to the other of said evaporators, said other evaporator having a header for collecting gaseous refrigerant, means including a restricted passage arranged in said conveying means for maintaining a difference of pressure between said evaporators, means including a tube communicating with said conveying means between said passage and said other evaporator and with said header.

- for diverting from said conveying means a quantity of gaseous refrigerant, and means for withdrawing gaseous refrigerant from said header.
6. A refrigerating machine including two evaporators, means for supplying refrigerant to one of said evaporators, the other at least of said evaporators being of the flooded type and comprising a header and a plurality of depending refrigerant circulating conduits, means for conveying liquid and gaseous refrigerant from said one evaporator to said other evaporator and for admitting a mixture of liquid and gaseous refrigerant to said other evaporator below the normal level of liquid refrigerant therein, means for withdrawing gaseous refrigerant from said header, means including a restricted passage arranged in said conveying means for maintaining a difference of pressure between said evaporators, and means including a tube communicating with said conveying means between said passage and said other evaporator and with said header for diverting from said other evaporator a quantity of gaseous refrigerant.
7. A refrigerating machine including two evaporators, means for supplying refrigerant to one of said evaporators, the other of said evaporators comprising a header and a plurality of flooded depending refrigerant circulating conduits and a series conduit for carrying refrigerant through a portion of said other evaporator and for conveying refrigerant to said flooded conduits, means for conveying liquid and gaseous refrigerant from said one evaporator to said series conduit, means for withdrawing gaseous refrigerant from said header, means including a restricted passage arranged in said conveying means for maintaining a difference of pressure between said evaporators, and means including a tube communicating with said conveying means between said passage and said series conduit and with said header for diverting from said series conduit a quantity of gaseous refrigerant.
8. A refrigerating machine including a cooling unit comprising two evaporators one arranged within the other, means for supplying refrigerant to the outer one of said evaporators, the inner one at least of said evaporators being of the flooded type and having a header and a plurality of depending refrigerant circulating conduits, means for conveying liquid and gaseous refrigerant from said outer evaporator to said inner evaporator and for admitting said liquid and gaseous refrigerant to said inner evaporator below the normal level of liquid refrigerant therein, means including a restricted passage arranged in said conveying means for maintaining a difference of pressure between said evaporators, and means including a tube communicating with said conveying means between said passage and said inner evaporator and with said header for diverting from said inner evaporator a quantity of gaseous refrigerant, and means for withdrawing gaseous refrigerant from said header.
9. A refrigerating machine including two evaporators, means for supplying refrigerant to one of said evaporators, an outlet connection for removing liquid and gaseous refrigerant from said one evaporator, an upright cylindrical vessel communicating with said outlet connection, means including a connection communicating with said vessel near the bottom thereof and with the other of said evaporators for conveying liquid and gaseous refrigerant to said other evaporator, means including a restricted passage arranged in said outlet connection for maintaining a difference of pressure between said evaporators, and means including a tube communicating with the upper end of said vessel for diverting from said other evaporator a quantity of gaseous refrigerant, and means for withdrawing gaseous refrigerant from said other evaporator and from said tube.
10. A refrigerating machine including two evaporators, means for supplying refrigerant to one of said evaporators, an outlet connection for removing liquid and gaseous refrigerant from said one evaporator, an upright cylindrical vessel communicating with said outlet connection, means including a connection communicating with said vessel near the bottom thereof and with the other of said evaporators for conveying liquid and gaseous refrigerant to said other evaporator, means including an adjustable valve arranged in said outlet connection for maintaining said evaporators at different pressures and for selecting the differential of pressures between said evaporators, means for maintaining said valve partially open at all times, means including a tube communicating with the upper end of said vessel for diverting from said other evaporator a quantity of gaseous refrigerant, and means for withdrawing gaseous refrigerant from said other evaporator and from said tube.

LEONARD W. ATCHISON.
